[57] ABSTRACT

Electrical waveforms of arbitrary shape are generated by pulsing a delay line and taking a signal from the line via conductive strips of varying width mounted parallel to the line and capacitively coupled to it. The signal variation with time corresponds to the variation of effective capacitance as the energizing pulse is propagated along the delay line. With strips suitably contoured, the waveforms may be applied to the orthogonal deflecting electrodes of a cathode ray tube to trace any desired character on the tube screen. For example, a font of 96 characters can be made available with three delay lines carrying strips formed by printed circuit techniques and controlled by relatively simple selection circuits. Described sampling techniques permit indefinite expansion of the time base of developed waveforms.

ALPHANUMERIC CHARACTER DISPLAY AND WAVEFORM GENERATOR THEREFOR

This invention relates generally to the generation of electrical waveforms of arbitrary shape.

Such waveforms are useful for many purposes, including, in particular, the production of selected alphanumeric characters on the screen of a cathode ray tube. For the sake of clarity, the invention will be described primarily with relation to such character generation, but without implying limitation of the invention to that particular use.

A primary object of the present invention is to permit economical and convenient generation of a wide variety of waveforms of arbitrary shape, free from the artificial shape limitations that are inherent in most previously available methods of waveform generation.

A further object of the invention is to provide waveform generating mechanism that is sufficiently economical and compact to make feasible the provision of a large vocabulary of relatively complex waveforms.

In the particular field of character generation, the invention permits each character to be displayed on a cathode ray tube by applying to the orthogonal deflecting electrodes a unique pair of waveforms of such shape that the complete character is traced as a single, effectively continuous operation. Characters traced in that manner may have any desired style, and typically appear more normal and artistic than characters generated by previously available means. Also, the invention makes feasible the display of many specialized configurations, such as mathematical and electronic symbols, Chinese and Japanese characters, and the like.

Present electronic character display systems generally provide means for tracing a limited variety of fixed character components, such as dots or line segments. A desired character is then approximated by assembling selected components. Characters may be produced, for example, by selective display of certain dots of a rectangular array, or certain line segments of a pattern.

The present invention, on the other hand, forms each character independently, with specially generated waveforms designed explicitly for that character. That approach not only permits complete freedom in designing each character. It also permits great simplification of the usual circuitry for selecting a desired character from the font of available characters. In accordance with the present invention, selection of a character requires in principle only the operation of a single switch for directing an energizing pulse to the waveform delineating mechanism for the desired character.

Waveform generating mechanisms in accordance with the invention are economical to fabricate, structurally simple and compact, and both convenient and reliable in operation. Those advantages result in large part from the fact that the critical portions of the structure can be fabricated by techniques that are well known in themselves and that are well adapted to miniaturization.

Those and other objects and advantages of the invention are attained by employing a delay or artificial transmission line for waveform generation. An energizing pulse is applied as input to one end of the delay line,

and an output signal is taken from the line via circuit means capacitively coupled to the line, typically along its entire length, the strength of coupling varying along the line in a manner corresponding to the desired waveform.

Delay lines are well known as a means for controlling the mutual time relation of discrete electrical pulses, as in U.S. Pat. No. 3,085,214, issued on Apr. 9, 1963 to Gordon C. Dewey, for example. However, delay lines have received little attention for generating continuously variable waveforms. U.S. Pat. No. 3,289,195, issued on Nov. 29, 1966 to Stephen E. Townsend, describes a method of generating alphanumeric characters with waveforms derived from a delay line by output windings inductively coupled to the line. However, the structures described by Townsend are inherently cumbersome in form and would be difficult and expensive to fabricate. The present invention overcomes those difficulties by the use of capacitive coupling and by providing structural features, to be described, which are made possible by such coupling.

The invention may utilize any form of delay line in which an input electrical pulse causes a charge to be propagated progressively along the length of the line. A particularly suitable type of delay line comprises a dielectric support form carrying a helical winding of fine wire, with an electrically conductive ground plane capacitively coupled to the winding. When an input pulse is supplied to one end of the winding and is absorbed by a suitable terminating impedance at the other end, an electrical charge is propagated with well-defined wave front along the line with a velocity determined by the parameters of the line. Those parameters include, in particular, the magnetic inductance of the winding and the distributed capacitance between the electrical winding and the ground plane. The supporting form and the winding may be cylindrical, but are preferably flat, so that the winding has two essentially plane faces.

In accordance with the present invention a desired waveform may be derived from a delay line of the general type described by mounting a strip of conductive material parallel to the line in mutually insulated, capacitive relation to it. The width of the strip is non-uniform, varying in such a way that the capacitance per unit length between the strip and the delay line varies along the line as a function of the desired waveform.

That capacitance variation may be gradual or stepwise. Several such strips are typically provided, each contoured to provide a distinct waveform, and mounted in closely adjacent relation opposing a face of the delay line.

As the wavefront from the input pulse travels along the delay line, a charge is induced in the adjacent portion of each of the strips. The magnitude of the charge appearing on each strip varies in direct proportion to the width of the strip at the point directly adjacent the wavefront. Hence the signal taken from a strip displays a definite time variation. The time component of that variation depends upon the speed of propagation of the delay line, while the amplitude of the variation is controllable by the contour of the strip.

The actual waveform obtained depends also upon the form of the energizing pulse applied to the delay line. For example, energization by a step voltage

produces a waveform that is the integral of that produced by a sharp input pulse. The final output can be further modified by processing the initially developed signal, as by suitable differentiating or integrating circuits, by sampling techniques, and the like. In particular, an initial waveform may represent a carrier frequency modulated by one or more desired waveforms, which are then produced by demodulation.

In practice, it is often desirable to provide two coupling strips having substantially complementary contours for generating each desired waveform. The complementary strips are coupled to the respective input terminals of a differential amplifier or its equivalent, so that both positive- and negative-going portions of an output waveform are symmetrically driven.

In accordance with a further aspect of the invention, each output strip takes the place of a portion of the ground plane of the delay line. In fact, the entire area of the ground plane, or a major fraction of it, is typically split into a multiplicity of generally parallel strips that are mutually spaced by intervals just wide enough to insure their electrical isolation. All of the strips are normally grounded. In order to generate a selected one of the available waveforms, the corresponding strip is disconnected from ground and is coupled to an output circuit, all other strips remaining grounded. The splitting of the ground plane into mutually insulated strips, and the isolation from ground of one strip, or of a small number of strips, has no significant effect on the characteristics of the delay line. When the strips comprise pairs with complementary shape they can utilize the entire ground plane. In any case, the strips can usually be shaped to nest in a manner to utilize most of the area of the ground plane, any remaining areas being permanently grounded.

With the structure just described, selection of a particular waveform requires only opening the circuit through which the selected strip is normally connected to ground, and connecting the strip instead to the output circuit. The latter connection may employ capacitive coupling, and no switching action is then required for it.

Each ground plane structure, embodying an array of output strips, is typically mounted on a support sheet of suitable dielectric material. The desired strip configuration can be reproduced on the sheet by use of photolithographic techniques and materials familiar to those skilled in the art of manufacturing printed circuit boards for electronic devices. Even highly intricate configurations can be produced by such techniques at virtually any scale that may be desired, permitting one delay line structure to generate selectively a large number of distinct waveforms. A principal advantage of the invention is the great ease and economy with which the described coupling structures can be fabricated.

When the generated waveforms are to be used for displaying alphanumeric characters on a cathode ray tube, two strips are ordinarily required for generating deflection waveforms for the x- and y-coordinates of each character. A third strip may be provided for developing a gating waveform for control of the intensity of the cathode ray beam. Since several characters may movement, identical movement patterns for either

the x- or the y-component of the movement the same output strip may be used for such a group of characters. Also, for some characters the y-axis can be generated as described, and a conventional time base used for the x-axis. However, in view of the great economy inherent in the present waveform generating structure, it will usually be more economical to provide separate strips for each character than to construct the additional selection circuits required for reducing the number of strips.

A particular advantage of the invention is that, so long as the cooperating waveforms for each character are derived from the same delay line, they are automatically developed in correct mutual phase relation.

The time base of waveforms developed in accordance with the invention can be varied considerably by suitable selection of the constants of the delay line, for example by winding the delay line on a form of ferrite or other magnetically permeable material to slow the propagation velocity of the wave front. In accordance with a further aspect of the invention, the time base of the generated waveforms may be expanded to any desired extent by pulsing the delay line periodically and sampling the resulting series of waveforms at progressively varying points. The sampled data are then assembled with suitable filtering to reproduce the waveform with time base corresponding to a complete cycle of sampling. With that modification, a character generating system in accordance with the invention can drive the x- and y-coordinates of a conventional pen recorder, for example, and is useful for drawing characters in connection with known types of automatic drafting system.

A full understanding of the invention, and of its further objects and advantages, will be had from the following description of certain illustrative manners of carrying it out. The particulars of that description, and of the accompanying drawings which form a part of it, are intended only as illustration and not as a limitation upon the scope of the invention, which is defined in the appended claims.

In the drawings:

FIG. 1 is a schematic perspective, partially broken away, representing an illustrative waveform generator in accordance with the invention;

FIG. 2 is a transverse section corresponding generally to FIG. 1;

FIG. 3 is a longitudinal section on line 3-3 of FIG. 2;

FIG. 4 is a schematic plan representing illustrative coupling strips, with schematic control circuits;

FIG. 5 is a simplified section corresponding to FIG. 3 and representing a modification;

FIG. 6 is a section on line 6-6 of FIG. 5;

FIG. 7 is a graph showing an output waveform corresponding to FIG. 6;

FIG. 8 is a series of schematic graphs illustrating waveforms generated under varying conditions;

FIG. 9 is a schematic diagram of a control system in accordance with the invention;

FIG. 10 is a schematic block diagram representing a system for expanding a waveform time base; and

FIG. 11 is a schematic diagram representing a system employing a carrier frequency.

As represented schematically in FIGS. 1 to 3, the waveform generating device 20 comprises the flat delay line 23 with array 30 of coupling elements 32 for generating selectively any one of a plurality of distinct waveforms. Delay line 23 comprises the winding 24 of fine copper wire wound on the flat dielectric form 22 with the longitudinal axis 21. Winding 24 is connected at one end to the input terminal 26 and at the other end to the output terminal 28, which is typically connected to ground through a terminating resistance 29, suitably matched to the characteristic impedance of the delay line to prevent reflection of pulses propagated along the line. Suitable magnetically permeable materials may be incorporated in form 22 for controlling the delay time. The transverse dimensions and shape of form 22 are ordinarily uniform throughout its length, but may be varied if desired to obtain special effects in accordance with the known principles of electromagnetism.

The array 30 of coupling elements 32 is mounted in parallel, closely spaced relation directly facing the winding of the delay line. A second complete assembly of coupling elements is typically mounted in corresponding relation to the other face of the delay line, as indicated in fragmentary form at 30a in FIG. 1. Such a second array is omitted in FIGS. 2 and 3 for clarity of illustration, but is suggested by indication of the mid-plane 37 of the assembly. The coupling elements 32 comprise thin strips of highly conductive material such as copper, and are typically deposited photolithographically in a predetermined pattern on the inner face of the support layer 36 of dielectric material. Each strip typically extends essentially the entire length of the delay line, and adjacent strips are spaced from each other by intervals 33 just sufficient to provide reliable insulation. The spacing of the entire array of strips from the delay line winding is accurately defined by the sheet 34 of dielectric material such as polystyrene. The thickness of that sheet may vary in predetermined manner if desired, to produce a corresponding variation in capacitance, but will be assumed to be uniform for clarity of description. The entire assembly is shielded from stray fields by the grounded enclosing shield 38 of electrically conductive material. If support sheet 36 is made much thicker than spacing sheet 34, the capacitance between each coupling element 32 and shield 38 is effectively negligible compared to that between the element and winding 24.

Winding form 22 may typically comprise a piece of epoxy circuit board 1/16-inch thick. Winding 24 may be close wound with No. 32 varnish insulated copper wire, yielding about 100 turns per inch. With ground plane array 30 spaced by layer 34 about 0.010 of an inch from the winding, a delay line eight inches long and four inches wide then produces a delay time of the order of 1 microsecond. Widely different delay times may be obtained in accordance with known electromagnetic principles by varying the dimensions and form of the described structures and by incorporating materials having specialized electromagnetic properties, such as ferrites, for example.

FIG. 4 represents in plan an illustrative array of coupling strips for generating typical waveforms suitable for producing selectively the two letters A and C on a cathode ray tube 40. For each letter, one pair of strips

X1 and X2 is employed for generating an X waveform for driving the x-component of the cathode ray beam deflection, while a second pair of strips Y1 and Y2 controls the y-component of the deflection. A third pair of strips Z1 and Z2 controls the beam intensity. All strips are normally grounded via the switches of relays RyA and RyC, which control the letters A and C, respectively. To display a letter, the corresponding relay coil is energized by current supplied from the selection circuit 42A or 42C, lifting ground from all strips for that letter and connecting them instead in pairs to the inputs of amplifiers MX, MY and MZ. As indicated schematically, the respective amplifier outputs control the deflection voltages applied to the x- and y-deflection plates 44 and the beam intensifying electrode 46 of the cathode ray tube. Separate beam positioning voltages, derived by known means not explicitly shown, are supplied to the deflection circuits to define the location on the screen of each character.

The coupling strips of each pair have straight outer edges and are separated from each other by a narrow slot 33. The widths of the two strips of each pair then vary in mutually complementary fashion. With the two strips connected to the respective input terminals of a differential amplifier the output waveform generated when the delay line is energized by a sharp pulse E corresponds closely to the shape of slot 33. The use of such strip pairs with complementary contours has the advantage that the output waveform can readily be driven both above and below ground potential. For that purpose the contours need not be strictly complementary, and departures from that relation may be useful under special conditions.

The strip contours shown in FIG. 4 illustrate in principle how two representative letters may be generated. The letter A is drawn in two strokes, between which the beam is blanked to permit repositioning for the second stroke. The letter C requires only one stroke, and the waveform for the intensity control is then very simple. In principle, the Z strips can be designed to compensate the beam intensity on the CRT screen for non-uniform deflection speed, but it is usually preferable to employ the Z strips only for switching the beam on and off without proportional modulation. Uniform line intensity on the CRT screen is then obtained by designing the strip contours to produce uniform deflection speed of the cathode ray beam along its path whenever the beam is not blanked. Alternatively, different strokes of a character, or different characters may be traced with different intensity, if desired, by intentionally modifying the waveforms to produce appropriate variations of beam velocity.

An alternative arrangement of coupling elements is shown in FIGS. 5 and 6 for producing waveforms that extend both above and below ground potential. Whereas the system of FIG. 4 provides two coupling elements of complementary form that are coupled to a common delay line and supply their signals to opposite terminals of a differential amplifier, the system of FIGS. 5 and 6 provides two delay lines that are energized by pulses of opposite polarity. Complementary coupling strips are coupled to the respective delay lines, and the charges on the two elements are added to provide a single output signal.

In the illustrative arrangement of FIG. 5, the two complementary coupling elements 32a 32b are carried on opposite faces of a common dielectric board 36a. That assembly is sandwiched between the two delay lines on the forms 22a and 22b with the respective input lines 26a 26b. Spacing layers and shields corresponding to those of FIGS. 1 to 3 are omitted in FIG. 5 for clarity. The two cooperating coupling elements are typically connected directly together through the support board, as indicated at 39, with the common output line 39a, may be connected by external circuitry. Input energizing pulses to the two delay lines are typically synchronized and of similar form but opposite polarity, as indicated at E1 and E2. FIG. 7 is a graph representing the type of output signal S corresponding to inputs E1 and E2 and to the illustrative coupling strip contours of FIG. 6. Modified results may be obtained with the same structure by employing energizing pulses that differ from each other in form, amplitude or timing.

As an alternative structure, the two distinct delay lines of FIG. 5 may be replaced by a single line of twice the length, supplied simultaneously with a positive input pulse at one end and a negative pulse at the other end. A single strip shaped like 32a of FIG. 6 for half its length and like a mirror image of 34b the other half, will then give an equivalent output.

FIG. 8 illustrates schematically the general manner in which the output from a contoured coupling element varies with different types of delay line energization and with different output circuit arrangements. The diagram shows in section A an illustrative strip contour, with two discrete changes of width and with a linear ramp region. Sections B and C show the waveform shapes resulting from pulse and step inputs, respectively, when the strip is floating and coupled capacitively to the output circuit, as in FIG. 4 after operation of one of the control relays RyA or RyC, for example. It is noted that waveform C corresponds to the integral of waveform B. Sections D and E of FIG. 8 show the waveforms obtained when the coupling strip is effectively grounded and the output signal is proportional to the current to ground. Such a signal may be taken in principle as the voltage drop across a resistor to ground, as indicated in the figure, or may be measured directly by a current responsive amplifier.

FIG. 9 represents schematically an illustrative system for selecting and displaying characters under control of a code representation of the character to be displayed. An important feature of the system shown is the utilization of several distinct delay lines for different groups of characters, so that selection of an individual character is carried out in two steps, typically under control of distinct digits of the complete digital code by which the characters are designated. One group of digits designates the delay line associated with the desired character, and directs an energizing pulse to that delay line; while another group of digits designates the particular character of the group associated with that delay line, and effectively connects the coupling strips for that character to the output circuit. That division of selection responsibility greatly reduces the total number of switching elements required for the entire selection function.

In FIG. 9 the numeral 50 designates a data processing device which produces on the lines b1, b2 . . . b7 a seven digit binary code representation of a character to be displayed, and at the same time generates on the line 52 an energizing pulse, typically a sharp voltage pulse as indicated at E. The complete font of available characters is assumed for purposes of illustration to include 96 characters, of which 32 are generated by each of the three delay lines indicated schematically at A, B and C. For clarity of illustration, only the input terminal 29 to the winding and the output terminals 35 from selected strips are shown explicitly for each delay line. Separate output terminals are indicated at X and Y for the x- and y-coordinates for each of the characters, which are numbered 1, 2, . . . 32 each delay line. Additional coupling strips may be provided, as already indicated, for controlling the beam intensity, but are omitted in FIG. 5 for clarity of illustration.

The X output terminals for characters A1, B1 and C1 are connected in parallel to the line DX1, and the X output terminals for the corresponding groups of characters with higher numbers are similarly connected to the respective lines DX2 to DX32. Those lines are connected to ground through the collector-emitter circuits of the respective switching transistors QX1 to QX32. The Y output terminals for the various characters are similarly connected to the lines DY1 to DY32, which are connected to ground through the respective transistors QY1 to QY32. Lines DX1 to DX32 are also coupled via the respective capacitors CX1 to CS32 to the line 47X, which is connected directly as input to the amplifier MX. Lines DY1 to DY32 are similarly coupled via the capacitors CY1 to CY32 to the line 47Y and thence to amplifier MY. Amplifiers MX and MY are typically broad band amplifiers such as are conventionally employed as video amplifiers in television systems.

Line 52 from data device 50 is connected in parallel via the respective resistances R1A, R1B, and R1C to the input terminals 29 of all three delay lines A, B and C. However, transmission of energizing pulses E to the delay lines is normally disabled by grounding of the input terminals via the respective switching transistors QA, QB and QC.

In order to control the switching transistors QA, QB, QC for the delay lines A, B and C and the transistors QX1 to QX32 and QY1 to QY32 for the output strips, the binary digital representation b1 to b7 is first decoded by the decoding circuits 60, 62 and 64, which are typically of conventional design and do not require detailed description. Decoder 60 receives as input the binary digital signals for the three digits b1, b2 and b3, which represent a particular one of eight possible values. The eight output lines 0 to 7 from decoder 60 are normally maintained at positive potential. In response to an input code signal the corresponding output line becomes grounded. Decoder 62 similarly receives input signals for the two digits b4 and b5 and produces as output signal grounded condition of the corresponding one of the four output lines 0 to 3, which are normally positive. The output lines from decoders 60 and 62 are coupled in matrix fashion via the summing resistances R3 to the output lines F1 to F32, according to the characters represented by the respec-

tive code configurations. Each line F1 to F32 is connected in parallel to the bases of both transistors QX and QY for the corresponding number 1 to 32. The values of resistors R3 are selected so that each of those transistors is maintained conductive when at least one of the associated output lines from decoders 60 and 62 is positive, and is cut off only when both those output lines are grounded. Accordingly, all outputs from the three delay lines A, B and C are disabled except for those that are isolated from ground by cutoff condition of the selected pair of transistors QX and QY, which correspond to the code representation b1 to b5 supplied from data device 50.

Decoder 64 receives as input the digital signals b6 and b7 and produces as output signal grounded condition of the corresponding one of the output lines A, B and C, which are normally positive. Those lines are connected through the current limiting resistors R2A, R2B and R2C to the bases of the respective transistors QA, QB and QC. Accordingly, energizing pulse E reaches only the one delay line A, B or C that corresponds to the code representation b6, b7. Those delay lines which do not receive an input pulse have no effect upon the ungrounded output line DX or DY except for contributing a small capacitance to ground.

The overall operation of the selection circuit is thus to deliver each energizing pulse E to only one delay line, and to disable all output signals from that line except one set. The resulting output signals supplied to the deflection electrodes 44 of cathode ray tube 40 produce the character represented by the code signals b1 to b7.

FIG. 10 illustrates a further aspect of the invention, by which a waveform generator of the general type already described may be modified to expand the time base of the resulting waveforms to any desired extent. The waveform generator 70 includes the delay line winding 72 with input line 73 and terminating resistance R5. The two output elements of complementary form 74a and 74b are capacitively coupled to the delay line and to the amplifier M4, producing on the line 78 a waveform 75 with time base corresponding directly to the delay time of the delay line. The two additional output elements 76a and 76b are coupled to the delay line and to the amplifier M6, producing the reference ramp function 77, which rises uniformly throughout the duration of waveform 75 and in definite phase relation to it.

The system of FIG. 10 is set in operation by a control pulse on the line 68. That pulse is supplied to the oscillator 71, which produces a continuing series of pulses E of suitable form for periodically energizing waveform generator 70. The control pulse on line 68 is also supplied to the ramp generator 80, which may be of conventional type and produces on the line 84 the control ramp function 82, which has typically the same total voltage rise as reference ramp 77, already described. However, the time base of control ramp 82 is entirely independent of the delay time of delay line 72, and is selected in accordance with the desired duration of the final output waveform. Control ramp 82 and reference ramp 77 are supplied as inputs to the coincidence circuit 86. That circuit typically produces a square wave pulse whenever ramp 77 exceeds ramp 82, and differentiates the resulting square waves to produce a

sharp positive pulse each time the ramps cross. Those pulses 87 are supplied via the line 88 as control signals to the gating circuit 90, which receives as input the original series of waveforms 75. In response to each control pulse 87, gate 90 supplies to output line 91 a voltage corresponding to the momentary value of waveform 75. Those output voltages are smoothed by lowpass filter 92, producing on the line 94 a reproduction 96 of waveform 75, but with its time base expanded to correspond to the duration of control ramp 82. The time base expansion produced by the system is readily variable by adjustment of ramp generator 80, and may represent many orders of magnitude.

When a waveform generator in accordance with the present invention is to be used for character generation the sampling technique represented illustratively in FIG. 10 provides useful flexibility. For example, a character generator designed for a cathode ray tube using electrostatic beam deflection can be modified by time base expansion to produce a waveform duration appropriate for a cathode ray tube with magnetic deflection. Also, by providing time base expansion of several orders of magnitude, a character generator of the present type can effectively drive a pen recorder having separate x- and y-axis drives. Such recorders are employed in automatic drafting machines of known type, but the character generating systems previously available for such machines tend to be extremely complex. By providing convenient and economical character generation for pen recorders and the like, the present invention permits great simplification of previously available automatic drafting machines.

In accordance with a further aspect of the invention, an initial waveform may be generated which represents modulation of a carrier frequency by the desired final waveform. That initial waveform may then be demodulated to produce the desired final waveform. An advantage of that procedure is that a single coupling strip 35 may be formed to represent two final waveforms, both modulating the same carrier frequency but in mutually displaced phase relation, as in conventional multiplex signal transmission. The two desired waveforms 40 may then be recovered from the initially generated waveform by phase sensitive demodulation, utilizing respective reference signals that have suitable phase relations. Such reference phase signals can be generated in any suitable manner, preferably by two 45 additional coupling strips associated with the same delay line that generates the initial waveform.

FIG. 11 represents schematically and in simplified form an illustrative system of the type just described. A delay line winding is indicated at 24c with input pulse E 55 and with an assembly 30c of coupling strips for generating three distinct waveforms A, B and C. The curves so designated in FIG. 11 show the shapes of the waveforms produced, and may be considered to represent the forms of the gaps between respective 60 pairs of coupling strips, such as those of FIG. 4, the strips themselves being omitted in FIG. 11 to simplify the drawing. Waveforms A and B are produced on the output lines 96A and 96B, respectively, and are supplied as reference phase signals to the respective demodulators 98 and 99.

The reference phase signals A and B comprise sinusoidal waveforms of constant amplitude mutually

displaced 90° in phase. Waveform C illustrates in simplified form how two distinct final waveforms are produced from a single initial waveform. The first half of waveform C is a sinusoidal curve of gradually decreasing amplitude in phase with reference wave A, while the second half of C has gradually increasing amplitude in phase with B. Waveform C is supplied via the line 97 as input to both demodulators 98 and 99. Demodulator 98 produces a waveform corresponding to the envelope of the component of the input signal in phase with reference A, as indicated in somewhat idealized form at 100. Demodulator 99 similarly responds only to the component of the input in phase with reference B, as indicated at 102. Those two final waveforms 100 and 102 can be employed, for example, to drive the x- and y-deflection circuits of a cathode ray tube, producing on the screen a letter L. The two phase components of waveform C are shown separated in time for clarity of illustration, but in practice may, of course, overlap in time.

I claim:

1. Mechanism for generating selectively individual continuous electrical waveforms having respective predetermined waveform shapes, comprising
delay line means including a delay line having an effectively flat surface and means for energizing the delay line to produce electrical wave front propagation along the surface longitudinally of the delay line,
an array of elongated conductive strips mounted in a common plane parallel to the delay line surface with the strips extending longitudinally of the delay line and capacitively coupled thereto,
said strips being uniformly spaced from the delay line surface by a sheet of dielectric material of a thickness that is uniform for all strips,
a plurality of said strips having widths which vary progressively along the strip length in accordance with said respective waveform shapes,
circuit means normally connecting the strips to a source of reference potential to form a ground plane for the delay line,
said circuit means including switching mechanism

for isolating selected strips of said plurality from the potential source,

and output circuit means coupled to at least the so selected strips to receive electrical signals therefrom in response to said wavefront propagation.

2. Mechanism as defined in claim 1, and in which a plurality of said strips are arranged in pairs of mutually adjacent strips with approximately straight parallel outer edges and with inner edges separated by a slot of approximately constant width, the strips of each pair having widths that vary in mutually complementary relation in accordance with one of said predetermined waveform shapes,

and said output circuit means include means for combining the signals received from the strips of a pair in opposite polarity to produce a unitary waveform.

3. Mechanism as defined in claim 1, and including means for periodically operating said delay line energizing means to generate a periodic series of essentially identical waveforms, means for deriving from successive waveforms of said series signals that represent the waveform amplitude at respective successive waveform portions, and means for deriving from such signals a waveform of similar shape but expanded time base.

4. Mechanism as defined in claim 1, and in which said width variations of at least one strip correspond to modulation of a carrier frequency by a predetermined waveform shape, and said output circuit means include phase sensitive circuit means for demodulating the initial waveform signal received from said strip to produce said waveform, structure capacitively coupled to said delay line for generating a reference phase signal having definite phase relation to said carrier frequency, and circuit means for supplying the phase signal as reference phase to the demodulating circuit means.
